UNITED STATES PATENT OFFICE

DOUGLAS B. GORDON, OF HAMILTON, ONTARIO, CANADA

DISPLAY DEVICE

Application filed April 23, 1928. Serial No. 272,203.

This invention relates to display devices and has for an object the provision of a device provided with a reflecting surface upon which certain symbols are projected from a transparent sheet of material.

Another object is to provide a display device wherein the symbols to be projected are preferably out of the line of vision of the person viewing the device.

10 Still another object is to so arrange the reflecting surface with respect to the symbols that the reflected images will simulate the real symbols in upright positions.

With the above and other objects in view, 15 the invention consists in certain novel features of construction, combinations and arrangement of parts as will be more fully described and particularly pointed out in the appended claims.

20 In the drawings:

Figure 1 is a perspective view of a display device constructed in accordance with the present invention;

25 Figure 2 is a fragmentary view of a portion of the display device shown in Figure 1; and

Figure 3 is a vertical section through the device.

Generally the device comprises an open face frame in the top of which is supported 30 a transparent sheet carrying the symbols to be displayed, while a second sheet having a reflecting surface is positioned below the transparent sheet and at an angle thereto, the arrangement being such that the light from 35 above will not only project the symbols upon the reflecting surface but will do so in such a manner that the images will assume upright positions.

Specifically the device comprises an open 40 face frame 10 having end walls 11 and 12 respectively and an inclined longitudinally extending wall 13 joining the two end walls. Each end wall is provided with an inwardly 45 projecting flange 14 at its top edge while a strip 15 is secured to each wall and is spaced from its respective flange 14 to form therewith a guideway 16, the rear end portion of each strip being bent toward the flange to form a stop 17. Preferably a second set of 50 strips 18 are secured to the end walls below

the first mentioned strips, each strip 18 being spaced above an end of the inclined wall 13 to form therewith a second guideway 19 on the end wall. Each strip 18 is likewise provided with an end portion which is bent toward the wall 13 to provide a stop 20.

With the above arrangement, there is provided an upper pair of horizontal guideways within which is adapted to be supported, a transparent sheet of glass 21 upon which suitable symbols 22 are formed by applying a coat of paint 22' to the glass and then cutting the preferred symbols into the paint. The lower pair of inclined guideways 19 is adapted to receive a sheet of material 23 having an inclined reflecting surface, both sheets being detachably secured in place by means of channel shaped finish strips 24 and 25 respectively which encase the outer edges of the sheets. These strips 24 and 25 are secured to the frame 10 in any desired manner such as by fasteners 26. To provide a neat appearance finish strips 40, 41, 42 and 43 of U cross section are used to conceal the edges of the metal above the glass 21. As shown, 70 the strips 40, 41 and 42 each embrace the edges of the top wall of the frame 10, whereas the strip 43 has an extension 43' secured in and carried by the strip 24.

With the device as thus constructed, it 80 will be apparent that if it is placed in a position where the transparent sheet is exposed to daylight, the symbols will be projected upon the surface 23 in such a manner that the reflected images assume positions disposed at 85 right angles to the real symbols. In use the device is adapted to be displayed with the open face directly in the line of vision of the person viewing the same. In this position the transparent sheet will be horizontally 90 disposed and usually out of sight with the reflecting surface at an acute angle to the latter, whereby the reflected images will assume vertical positions and appear to stand up from the reflecting surface.

95 The reflecting surface is shown in the present instance as being disposed at an angle of 45° to the transparent sheet and in this position the reflected images will be the same size as the real symbols. It is of course evident 100

- that by changing the angle of the reflecting surface from 45° , the reflected images will appear either taller or shorter than the real symbols according to the direction in which the surface is shifted. It will also be apparent that my display device may be used at night as well as in the day time by positioning a source of illumination above the transparent plate and to one side thereof.
- 10 While the above described frame is shown as the preferred form of supporting means for the sheets, it is of course evident that any desired means may be employed for positioning one sheet relative to the other so as to obtain the required results. With the present construction, should either of the sheets be broken or if it is desired to substitute new sheets, it will be necessary only to remove one or the other of the finish strips 24 and 20 25, slip out the sheet in question, slide the new sheet into place and then secure its respective finish strip to the frame.

From the foregoing it will be apparent that I have provided a display device which may be used in many different ways for display and advertising purposes, this device being simple in design and economically manufactured.

While it is believed that from the foregoing description, the nature and advantages of the invention will be readily apparent, I desire to have it understood that I do not limit myself to what is herein shown and described and that such changes may be resorted to when desired as fall within the scope of what is claimed.

What I claim as my invention is:

1. In a display device, a frame having spaced end walls provided with inwardly projecting flanges at their top edges, angular strips secured to the end walls and having inwardly extending flanges spaced from the flanges aforesaid and cooperating therewith to form guideways, an inclined wall joining said end walls, a second set of angular strips secured to said end walls adjacent said inclined wall and forming therewith guideways, a sheet of material having a reflecting surface supported upon said inclined wall and secured in said last mentioned guideways.
2. In a display device, a frame having spaced end walls provided with inwardly projecting flanges at their top edges, angular strips secured to the end walls and having inwardly extending flanges spaced from the flanges aforesaid and cooperating therewith to form guideways, an inclined wall joining said end walls, a second set of angular strips secured to said end walls adjacent the end portions of said inclined wall and forming therewith guideways, a sheet of material having a reflecting surface supported in said
- first mentioned guideways, a transparent sheet of material having symbols applied thereto, positioned in said top guideways, and means for detachably securing said sheets in said guideways including channel shaped finish strips encasing the outer edges of said sheets.
3. In a display device, a frame having end walls, the end walls being spaced laterally apart, and having inturned flanges at their upper ends, an inclined wall extending between said end walls with opposite ends of said inclined wall secured to said end walls and with the lower edge of said inclined wall at the lower edges of said end walls, said inclined wall having an upstanding extension at its upper end provided with an inturned flange that overlaps and is secured to the inturned flanges of said end walls, a sheet of transparent material parallel to said first mentioned inturned flanges, a sheet of material parallel to said inclined wall and having a reflecting surface, and means associated with said end walls for holding the two sheets aforesaid in position.
4. In a display device, a frame having end walls, and an intermediate inclined wall, the end walls being spaced laterally apart and having inturned flanges at their upper ends, the inclined wall extending between said end walls with opposite ends of said inclined wall secured to said end walls and with the lower edge of said inclined wall at the lower edges of said end walls, said inclined wall having an upstanding extension at its upper end provided with an inturned flange that is secured to the inturned flanges of said end walls, a sheet of transparent material parallel to said first mentioned inturned flanges, a sheet of material parallel to said inclined wall and having a reflecting surface, a strip detachably secured to the end walls and retaining the sheet of transparent material in position, and a strip embracing the lower edge of the inclined wall and the lower edge of the last mentioned sheet, retaining the latter relative to the inclined wall and having portions secured to said end walls.
5. In a display device, a frame having spaced end walls provided at their upper edges with inturned flanges, an intermediate wall terminally connected to the said end walls and provided at its upper edge with an extension having an inturned flange, and strips secured to the end walls beneath the first mentioned inturned flanges and having inwardly extending flanges spaced from and cooperating with the said inturned flanges of the end walls and with the inturned flange of the intermediate wall to form guideways for sheet material.
6. In a display device, a frame having spaced end walls provided at their upper edges with inturned flanges, strips secured to the end walls beneath said inturned flanges

and having inturned flanges substantially parallel to the inturned flanges of the end walls and forming therewith guideways for sheet material, an intermediate wall terminally connected to said end walls and provided at its upper edge with an inturned flange that extends over the strips aforesaid, and abutments for sheet material carried by said strips beneath and extending toward said last mentioned inturned flange.

7. In a display device, a frame having spaced end walls provided at their upper edges with inturned flanges, and an inclined wall terminally connected to the end walls, the lower edge of said inclined wall being adjacent the lower edges of said end walls, said inclined wall being provided at its upper edge with an extension having an inturned flange secured to the inturned flanges of the end walls.

8. In a display device, a frame having spaced end walls, strips secured to the inner faces of said end walls adjacent the upper edges thereof and having inturned flanges spaced from said upper edges and constituting slides for sheet material, strips at the inner ends of said flanges for limiting inward sliding movement of the sheet material, and means associated with the upper edges of the end walls for retaining sheet material on the inturned flanges of said strips.

9. In a display device, a frame having spaced end walls, strips secured to the inner faces of said end walls adjacent the upper edges thereof and having inturned flanges spaced from said upper edges and constituting slides for sheet material, strips at the inner ends of said flanges for limiting inward sliding movement of sheet material, and a connection between said end walls having an inturned flange overlapping said strips for retaining sheet material on the inturned flanges of the strips.

10. In a display device, a frame having spaced end walls, strips secured to the inner faces of said end walls adjacent the upper edges thereof and having inturned flanges spaced from said upper edges and constituting slides for sheet material, strips at the inner ends of said flanges for limiting inward sliding movement of the sheet material, and means separable from but normally terminally connected to said end walls and having means overlapping said strips for retaining sheet material on the inturned flanges of the strips.

11. In a display device, a frame having spaced end walls, strips secured to the inner faces of said end walls adjacent the upper edges thereof and having inturned flanges spaced from said upper edges and constituting slides for sheet material, strips at the inner ends of said flanges for limiting inward sliding movement of the sheet material, a connection between said end walls

having an inturned flange overlapping the inner ends of said strips for retaining the sheet material on the inturned flanges of the strips, and means separable from but normally terminally connected to said end walls and having means overlapping the outer ends of said strips for retaining sheet material on the inturned flanges of said strips.

12. In a display device, a frame having spaced end walls, and an inclined wall constituting a slide for sheet material extending between and having lateral flanges secured to said end walls, strips secured to said end walls and having inturned flanges spaced from and serving to guide sheet material on said inclined wall and having other flanges at their inner ends extending toward said inclined wall and limiting inward sliding movement of sheet material between said inclined wall and inturned flanges of said strips, and means separable from but normally extending between and connected to said end walls for limiting outward sliding movement of sheet material from between said inclined wall and the flanges aforesaid of said strips.

In testimony whereof I affix my signature.
DOUGLAS B. GORDON.
